INVENTOR

UNITED STATES PATENT OFFICE

100,431

DESIGN FOR A NEGLIGEE

Julia Lutfy, New York, N. Y.

Application June 13, 1936, Serial No. 63,270

Term of patent 3½ years

To all whom it may concern:

Be it known that I, Julia Lutfy, a citizen of the United States of America, residing in Manhattan, county of New York, and State of New York, have invented a new, original, and ornamental Design for a Negligee, of which the following is a specification, reference being had to the accompanying drawing, forming part thereof, wherein,

I claim:

The ornamental design for a negligee, substantially as shown.

JULIA LUTFY.
